UNITED STATES PATENT OFFICE.

GUSTAV RADTKE, OF CHICAGO, ILLINOIS.

COMBINED WRENCH AND PIPE-CUTTER.

No. 893,369.

Specification of Letters Patent.

Patented July 14, 1908.

Application filed February 7, 1908. Serial No. 414,789.

To all whom it may concern:

Be it known that I, GUSTAV RADTKE, a citizen of the United States, residing at Chicago, in the county of Cook and State of Illinois, have invented certain new and useful Improvements in a Combined Wrench and Pipe-Cutter; and I do hereby declare the following to be a full, clear, and exact description of the invention, such as will enable others skilled in the art to which it appertains to make and use the same.

My invention relates to new and useful improvements in a combined wrench and pipe cutter and my object is to provide means for readily and quickly adjusting the movable jaw towards or from the fixed jaw.

A further object is to provide means for directing the cutting mechanism into engagement with a pipe under pressure and a still further object is to so construct the parts of the wrench that they may be quickly assembled.

Other objects and advantages will be hereinafter referred to and more particularly pointed out in the claims.

In the accompanying drawings which are made a part of this application, Figure 1 is an elevation partly in section of my combined wrench and pipe cutter. Fig. 2 is a sectional view thereof, as seen on line 2—2, Fig. 1. Fig. 3 is a sectional view as seen on line 3—3, Fig. 1, and, Fig. 4 is a sectional view as seen on line 4—4, Fig. 1.

Referring to the drawings in which similar reference numerals designate corresponding parts throughout the several views, 1 indicates the shank of my improved wrench, to one end of which is fixed a jaw 2, the shank 1 being provided with threads 3 on a portion 30 of its length, which are adapted to enter a socket 4 and engage threads 5 therein.

The upper end of the socket 4 is provided with a pair of collars 6 and 7, said collars being spaced apart to form a channel 8 adjacent the upper end of the socket, in which is adapted to fit a substantially semi-circular tongue 9 on the lower edge of a movable jaw 10, the socket 4 being employed to adjust the movable jaw towards or from the fixed 40 jaw by rotating the socket on the shank 1.

In order to hold the movable jaw 10 in alignment with the fixed jaw 2, the shank 1 is flattened on diametrically opposite sides, as shown at 11, the opening 12 through the 50 movable jaw being constructed in such manner as to snugly fit around the shank 1. To

better obtain a firm hold upon the socket 4, in order to positively rotate the same, the peripheral surface thereof is roughened, or milled, as shown at 13.

The gripping faces of the jaws 2 and 10 at one side of the shank 1, are adapted to be used as a wrench and may be provided with teeth 14 and 15 respectively, when the wrench is employed for turning pipes, or other objects having round surfaces, while the gripping face of the jaw 2 at the opposite side of the shank 1 is concaved and the opposite face of the jaw 10 correspondingly convex to extend a cutting disk 16, carried by the jaw 10 between a pair of similar disks 17 and 18, carried by the jaw 2, said disks 17 and 18 being spaced an equal distance from the outer end of the jaw and shank 1, respectively, the disk 16 being so located on the jaw 10 as to extend midway between the disks on the jaw 2, and it will be readily seen that when a pipe is clamped between the disks 17 and 18 and the disk 16 and the wrench rotated around the pipe, said pipe 80 will be severed at this point.

The disks are forced firmly into engagement with the pipe by turning the socket 4 onto the shank 1 and in order to obtain a sufficient pressure to cause the disks to enter 85 into the pipe, I secure to the outer end of the socket 4, a handle 19, having at its outer end a cross bar 20, whereby rotating motion may be readily imparted to the handle, the inner end of the handle being fixed to the socket 4 in any preferred manner, as by introducing 90 bolts or rivets 21 through the socket and the inserted portion of the handle.

In assembling the parts of the wrench, the tongue 9 is first entered in the channel 8 and the shank 1 then introduced through the opening 12 in the movable jaw 10, until the threaded portion of the shank engages the threads in the socket, when the socket may be rotated either by grasping the cross bar 100 20 or milled portion of the socket and rotating the same and in cutting a pipe, it will be understood that after the wrench has been turned around the pipe one or more times, the handle and socket are rotated and the 105 disks again forced into engagement with the pipe, this operation being repeated until the pipe is completely severed.

It will thus be seen that I have provided a very cheap and economical form of combined wrench and pipe cutter and one that will be positive in its operation and readily applied 110

to use. It will further be seen that the several parts of the wrench may be readily assembled and the movable parts of the jaw adjusted towards or from the fixed jaw.

5 What I claim is:

A wrench of the class described, comprising a shank having flattened portions, threads on a portion of said shank and a jaw fixed to one end of the shank; of a movable jaw having an opening therein, conforming to the contour of the shank, whereby the movable jaw is held in alinement with the fixed jaw, a socket having threads therein adapted to engage the threads on the shank, 10 collars adjacent one end of the socket, spaced apart to form a channel, a semi-circular |

tongue on the movable jaw adapted to enter said channel, the free ends of the tongue being parallel and extending a slight distance beyond the center of the socket, a handle 20 fixed to one end of the socket and a cross bar on said handle, whereby the socket may be readily rotated and the movable jaw adjusted with respect to the fixed jaw.

In testimony whereof I have signed my 25 name to this specification in the presence of two subscribing witnesses.

GUSTAV RADTKE.
